UNITED STATES PATENT OFFICE

122,733

DESIGN FOR A SADDLE BAG FOR MOTOR- CYCLES OR THE LIKE

Joseph Buegeleisen, Detroit, Mich.

Application May 31, 1940, Serial No. 92,713

Term of patent 14 years

To all whom it may concern:

Be it known that I, Joseph Buegeleisen, a citizen of the United States of America, residing at Detroit, county of Wayne, and State of Michigan, have invented a new, original, and ornamental Design for a Saddle Bag for Motorcycles or the like, of which the following is a specification, reference being had therein to the accompanying drawing, forming a part thereof, wherein:

Figure 1 is a side elevation of a saddle bag for motorcycles or the like, showing my new design;

I claim:

The ornamental design for a saddle bag for motorcycles or the like, substantially as shown.

JOSEPH BUEGELEISEN.
